UNITED STATES PATENT OFFICE.

ALFRED JACCARD ROD, OF STE. CROIX, SWITZERLAND, ASSIGNOR TO
HERMANN CHORENS, OF STE. CROIX, SWITZERLAND.

DEVICE FOR MECHANICALLY SUBSTITUTING ONE DISK FOR ANOTHER IN MUSIC-PIECES.

SPECIFICATION forming part of Letters Patent No. 749,826, dated January 19, 1904.

Application filed January 15, 1900. Serial No. 1,539. (No model.)

To all whom it may concern:

Be it known that I, ALFRED JACCARD ROD, a citizen of the Republic of Switzerland, and a resident of Ste. Croix, in the canton of Vaud, Switzerland, have invented certain new and useful Improvements in Devices for Mechanically Substituting One Disk for Another in Musical Instruments, of which the following is a specification.

10 My invention relates to apparatus whereby perforated music-disks may be mechanically interchanged from inoperative to operative positions in instruments of the class in which such disks are employed; and it consists of the construction, arrangement, and combination of parts, as fully described hereinafter.

In the accompanying drawings, Figure 1 is a front elevation of a machine embodying my improvements. Fig. 2 is a side elevation of 20 the same looking from the left-hand side of Fig. 1. Fig. 3 is a cross-section on line A B of Fig. 1. Fig. 4 is a top plan view of the upper portion of the machine. Figs. 5 and 6 are details showing the automatic grasping 25 and releasing device which constitutes an important feature of my invention. Fig. 7 is a detail in elevation, on an enlarged scale, of the disk-holder and guide. Fig. 8 is a top plan view of the parts shown in Fig. 7. Fig. 9 is 30 a detail of the snail-wheel and adjacent parts. Fig. 10 is a detail showing the operation of one of the levers employed in the machine.

Each perforated disk 1 is of the usual pattern, is provided with a row of holes 1^a near 35 its periphery in addition to the perforations which engage the teeth of the usual musical comb, and is vertically mounted on a horizontal shaft 2, fixed on a metal rod 3, the upper end of which is connected to a cord 5, 40 which extends over guide-pulleys 4 and carries at its opposite end a hollow socket 47. The pulleys 4 are mounted on a common frame-support 6, adapted to be moved horizontally toward and away from the front of the machine or apparatus on two guide-rods 9, such movements being imparted by any suitable means operated by hand or mechanically, whereby the respective disks may be brought into operative relations with the co-operating

mechanism. In the bottom of each socket is 50 an opening 48, the sides of which, flare downwardly and outwardly to facilitate the entrance of the upper end of a vertical rod 10 when a socket has been brought directly over said rod by the movement of the support 6. 55 The rod 10 is provided in its upper end with a groove 50, Fig. 6, in which is pivoted the lower end of a hook 51, which is normally pressed outwardly by a spring 52, secured in the groove. The rod is adapted to move vertically in a bearing 10^a and carries at its lower end a balance-weight 49. When the rod moves upwardly, its pointed upper end enters the opening 48 of the socket, which has been brought directly over the rod, the end of the 60 hook 51 being pushed back into the groove by the sides of the opening, and when the end is beyond the opening and within the socket the spring 52 presses outwardly the hook, which is thereby positively connected 65 with the socket, so that the following downward movement of the rod carries with it the socket, thereby pulling down the socket end of the cord 5 and correspondingly elevating the disk end of said cord, and hence the disk 70 which happens to be then attached to the rod 3, which is connected with that cord. The hook 51 is formed with a shoulder 51^a just below its upper end, which when the rod 10 moves downwardly engages the sides of the 75 opening in the bracket 54, thereby pushing the hook into the groove against the tension of the spring and thus releasing the socket, the downward movement of the latter being limited at a point above the corresponding 80 movement of the rod.

The rod 10 is connected to a lever 75 by a link 75^b, which is pivoted to the lever at 77 and to the rod near the bearing 10^a. Said lever is provided at its free end with a lug 53, 90 which engages one end of a horizontally-mounted lever 16, the opposite end of which is pivoted at 15. Near the center of the lever 16 and projecting from its upper side is a pin 17^a, which is in constant frictional contact with the periphery of a snail-wheel 18. This wheel is fixed on the shaft 21, which rotates with the drum 20 in the direction indi-

cated by the arrow *y* in Figs. 2 and 3. Any suitable means for driving said drum may be employed, the same forming no part of this invention. As the snail-wheel rotates the pin 17^a is progressively moved from the smallest to the greatest radius of the wheel, thus causing a greater or less movement of the lever 16 in the arc in which it reciprocates. At the greatest radius of the wheel the lever will be moved outwardly to its full limit, and thereby produce a corresponding movement to the lever 75, the effect of which will be to push upwardly the rod 10 through the connecting-link 75^b. As the pin reaches the smallest radius of the wheel the pressure on the lever 16 will be relieved, and the lever and rod will be returned to their normal positions through the medium of the weight 49. The movements of the levers 16 and 75 are clearly indicated in Figs. 9 and 10.

Each of the rods 3 supporting the shafts of the disks has a hook portion 55 at its upper end, which is adapted when the rod is elevated or in its upper position to be engaged by a dog 56, actuated by a spring 56^a and secured to the frame 6, and thus maintain the particular disk connected with such rod in its elevated and inoperative position. Each dog is provided with a pin 57 at its outer end, and as the frame is moved said pins are brought successively in juxtaposition to the pin 58 in the arm 78 of the shaft 59. This shaft is journaled in bearings 79 and 80 and has a crank-arm 81 opposite the arm 78. The arm 81 is connected by a link 60 with the arm 60^a of a bell-crank lever pivoted at 62, the other arm 83 of which engages the slotted end of a horizontal lever 64. This lever is pivoted at 82 and is held in its normal position by a spring 63, which is connected with the slotted end of the lever.

On the drum-shaft 21 above the snail-wheel is fixed an arm 37, in the outer end of which is a pin 38, which passes through the arm and projects above and below the same. The lower projecting part of the pin engages once at each revolution of the shaft the free and curved end of the lever 64 to move the latter outwardly against the tension of its spring 63, as indicated by the arrow *x* in Fig. 3, thus partially rotating the shaft 59 through the connections 83, 60^a, 60, and 81. As the shaft is so moved the pin 58 engages the pin 57 of the adjacent dog 56, moves the latter away from the hook 55 of the rod 3, and the disk which has been supported on said rod is released and will drop by gravity into operative position, in which the shaft 2 thereof is caught and held in the recess of a support 40, secured to the center of the bar 24. The bar 24 and the lower bar 25 furnish bearings in which are journaled the studs 84 and 30 of the roller-carrier 21^a, the rollers 22 of which are held against the lowered disk to maintain the latter in contact with the parts which actuate the

teeth of the musical comb by the action of a spring 35 on an arm or lever 34, which is pivoted at 33 and connected by a link 27 to the arm 31, which is connected to the stud 30 of the roller-carrier 21^a, as shown in Fig. 3. 70

66 represents an arm fixed on the stud 84 at a point above the shaft 2 and adapted to engage said shaft to maintain the disk in operative position and to be released therefrom when it is desired to put the disk out of operative position. 75

The lever 34 is provided on its under side with an extension 36, which when the drum rotates is engaged by the upper part of the pin 38 on the arm 37, thus moving said lever outwardly against the tension of its spring 35, and thereby partially rotating the roller-carrier through the parts 27 and 31, the effect of which is to move the rollers out of contact with the disk and at the same time disengage the 85 arm 66 from the shaft of the disk to permit the latter to be drawn up out of operative position. The periphery 42^a of the drum is in constant frictional contact with a friction-disk 42, fixed on a vertical shaft 41, the upper 90 end of which carries a wheel 43, in the periphery of which are fixed pins which are adapted to engage the holes 1^a in the disks, and thereby rotate the latter.

In the periphery of each disk is a notch 71, 95 which is engaged by a roller 72, mounted in the outer end of an arm 74^a, pivoted to the upper part of the rod 3. To prevent the rod 3 from moving with the rotation of the disk, I attach thereto a cord 75^c, which has its opposite end fastened to the frame 76, the outer end of which is at the side of the disk opposite to the direction of the movement of the latter. 100

Having thus described my invention, what 105 I claim as new, and desire to obtain by Letters Patent, is—

1. In an apparatus of the character described, a plurality of music-disks, an adjustable frame, cords suspended from said frame and connected at one end with said disks, sockets secured to the other end of said cords, a rotatable drum, means operated by said drum for engaging and drawing down said sockets whereby the disks are raised into inoperative 115 positions, and means for holding the disks in inoperative positions.

2. In an apparatus of the character described, a plurality of music-disks, an adjustable frame, cords suspended from said frame each of said cords connected at one end with a disk, sockets secured to the free ends of said cords, a hooked rod adapted to engage said sockets successively, means for disengaging the rod from said sockets, and means for raising and for lowering said rod. 120

3. In an apparatus of the character described, a plurality of music-disks, an adjustable frame, cords suspended from said frame and having one end connected with said disks, 130

sockets secured to the opposite ends of said cords, means for automatically engaging and disengaging said sockets, said means being adapted to draw downwardly said sockets when engaged therewith, means for rotating said disks and means for preventing their accidental rotation.

4. In an apparatus of the character described, a plurality of musical disks, an adjustable frame, cords suspended from said frame and connected with said disks, sockets secured

to the free ends of said cords, a suitably-driven drum, means operated by said drum for engaging and drawing down said sockets substantially in the manner and for the purpose set ¹⁵ forth.

In testimony whereof I have hereunto set my hand in presence of two witnesses.

ALFRED JACCARD ROD.
